Specification for Design.

Patented Nov. 11, 1919.

Application filed September 6, 1919. Serial No. 322,198. Term of patent 14 years.

To all whom it may concern:

Be it known that I, HORACE R. YARDLEY, a citizen of the United States, residing at Chicago, in the county of Cook and State of Illinois, have invented a new, original, and ornamental Design for a Lighting-Fixture, of which the following is a specification, reference being had to the accompanying drawing, forming part thereof.

Fig. 2 shows an inverted plan view of the body portion of my design.

I claim:

The ornamental design for a lighting fixture, as shown.

HORACE R. YARDLEY.
